US0D1030744S

(12) **United States Design Patent** (10) Patent No.: **US D1,030,744 S**
(45) Date of Patent: ** Jun. 11, 2024

(54) **NOTEBOOK COMPUTER**

(71) Applicant: **Samsung Electronics Co., Ltd.**, Suwon-si (KR)

(72) Inventor: **Wonkyung Jang**, Suwon-si (KR)

(73) Assignee: **SAMSUNG ELECTRONICS CO., LTD.**, Suwon-si (KR)

(**) Term: **15 Years**

(21) Appl. No.: **29/841,825**

(22) Filed: **Jun. 8, 2022**

(30) **Foreign Application Priority Data**

Dec. 9, 2021 (KR) 30-2021-0059368

(51) **LOC (14) Cl.** **14-02**

(52) **U.S. Cl.**

USPC **D14/315**

(57) **CLAIM**

The ornamental design for a notebook computer, as shown and described.

DESCRIPTION

FIG. 1 is a front perspective view of a notebook computer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The evenly-dashed broken lines in the drawings illustrate portions of the notebook computer that form no part of the claimed design.

1 Claim, 7 Drawing Sheets
